No. 37,420.

Patented April 25, 1905.

UNITED STATES PATENT OFFICE.

NAJEEB NAJA, OF NEW YORK, N. Y.

DESIGN FOR A PILLOW-SHAM.

SPECIFICATION forming part of Design No. 37,420, dated April 25, 1905.

Application filed February 10, 1905. Serial No. 245,138. Term of patent 3½ years.

To all whom it may concern:

Be it known that I, NAJEEB NAJA, a subject of the Sultan of Turkey, residing in the city and county of New York, State of New York, have invented a new, original, and ornamental Design for Pillow-Shams, of which the following is a specification, reference being had to the accompanying drawing, forming part thereof.

The drawing shows a representation embodying my design.

I claim—

The ornamental design for a pillow-sham, as shown.

NAJEEB NAJA.
